UNITED STATES PATENT OFFICE

HAROLD H. PELZER, OF ASTORIA, NEW YORK, ASSIGNOR TO STANDARD AUTOMATIC CANDY CORPORATION, OF NEW YORK, N. Y., A CORPORATION OF NEW YORK

DESIGN FOR A VENDING CABINET

Application filed March 31, 1932. Serial No. 43,350. Term of patent 7 years.

To all whom it may concern:

Be it known that I, HAROLD H. PELZER, a citizen of the United States of America, and a resident of Astoria, in the county of Queens, city and State of New York, have invented a certain new, original, and ornamental Design for a Vending Cabinet, of which the following is a specification, reference being had to the accompanying drawing, forming part thereof.

In the drawing Figure 1 is a front eleva-

tion of the cabinet embodying my design and Figure 2 is a top plan view of the cabinet; the rear of the cabinet being flat and without ornamentation.

What I claim is:

The ornamental design for a vending cabinet as shown and described.

This specification signed at New York city, in the county and State of New York, this 30th day of March, 1932.

HAROLD H. PELZER.
